(57) **CLAIM**

The ornamental design for a pump head, as shown and described.

DESCRIPTION

FIG. 1 illustrates a side view of the pump head;
FIG. 2 illustrates a side view of the pump head of FIG. 1;
FIG. 3 illustrates a front view of the pump head of FIG. 1;
FIG. 4 illustrates a rear view of the pump head of FIG. 1;
FIG. 5 illustrates a top view of the pump head of FIG. 1;
FIG. 6 illustrates a bottom view of the pump head of FIG. 1;
FIG. 7 illustrates a perspective view of the pump head of FIG. 1; and,
FIG. 8 illustrates a perspective view of the pump head of FIG. 1.

The broken lines in the drawings depict environmental subject matter only and form no part of the claimed design.
